UNITED STATES PATENT OFFICE.

HENRY C. HAM, OF LIBERTY, INDIANA, ASSIGNOR TO RUDE BROTHERS MANUFACTURING COMPANY, OF LIBERTY, INDIANA.

FORCE-FEED SEEDING-MACHINE.

SPECIFICATION forming part of Letters Patent No. 758,134, dated April 26, 1904.

Application filed September 27, 1902. Serial No. 125,090. (No model.)

To all whom it may concern:

Be it known that I, HENRY C. HAM, a citizen of the United States, and a resident of Liberty, in the county of Union and State of Indiana, have invented a certain new and useful Improvement in Force - Feed Seeding - Machines, of which the following is a full, clear, and exact description, reference being had to the accompanying drawings, which form part 10 of my specification.

My invention relates to force-feed seeding-machines of the class in which the seed is fed by means of a fluted wheel revolving with a correspondingly-fluted rosette or rose-washer which prevents the escape of grain at its end, with the usual cut-off for regulating the rate 15 of feed for different grains.

The object of my invention is to provide a combined rim and flute feed. It is so constructed and arranged that when the fluted wheel is entirely out of the cup a rim-feed remains for feeding a small amount of grain; but when the fluted wheel is within the cup for feeding a larger amount of grain the rim-feed is combined with the flute-feed, so as to 25 produce a continuous feed and prevent the objectionable "bunching" which has heretofore characterized the flute-feed.

The advantages of my construction will appear more fully as I proceed with my specification.

In the drawings, Figure 1 is a top plan view of a seed-cup to be attached to the bottom of a grain-hopper provided with my improved feeding mechanism. Fig. 2 is a section of Fig. 1 on the line 2 2; and Fig. 3 is a rear elevation, shown partly in section, on the line 3 3 of Fig. 2. Fig. 4 is a rear elevation, shown partly in section, with the flute-wheel pushed 35 completely out of the cup.

A is the usual seed-cup, made in sections A' A'', secured together by means of the lips a a', the whole cup being adapted to be attached to the bottom of a grain-hopper in the 40 usual manner.

B is the fluted wheel, and C the sleeve, provided with the cut-off gates D and E, both

mounted on a slidable shaft in any customary manner, so that the first is rotatable and the second fixed.

F is the rosette or rose-washer through which the fluted wheel B projects and in which it has bearing at one end, as usual, having flutes to correspond with the flutes of the fluted wheel. The rosette is provided with a shallow flange F', which at its inner edge is sharply inclined to the vertical. This inner inclined edge is provided with a number of short ribs f, which preferably correspond in number to the number of flutes on the fluted wheel. The rosette is provided with a boss f', which fits in a corresponding recess on the inner face of the section A'' of the seed-cup, in which it is held by means of a depending flange b at the top of the section A' and by the inner edge of said section A' at the bottom, where it rises slightly above the bottom edge of the rosette, as seen at b', Fig. 3.

The inside edge of the section A'' of the seed-cup is provided with a flange c, which completely covers the outside edge of the rosette toward the bottom of the cup, but tapers off toward the top, so as to leave the outside rim of the rosette entirely uncovered at the top.

G is the lip of the grain-cup, over which the grain passes into the tube and is cut off flush with the outside face of the gate E, so that no grain will collect behind it. The gate E is slightly shorter than the sleeve C by an amount equal to the depth of the flange on the rosette, so that when the fluted wheel B is pushed completely out of the cup, so as to have its inner end flush with the inner face of the rosette, a space is left between the end of the gate E and the inner face of the rosette. When the parts are in this position, the mechanism feeds simply as a rim-feed, the ribs f' elevating the grain and the inclination of the inner edge of the flange causing the grain to be thrown over onto the gate E, from which it slips or slides into the grain-tube, this being made possible by the fact that the lip G is flush with said gate.

- This feed is used when small grain is being sown. When it is desired to sow larger grain or a greater quantity of the smaller grain, the flute-wheel B is drawn into the cup a suitable amount, in which case the flute-feed is combined with the rim-feed. The rim-feed acts in the same manner, as above described, in the case when the fluted wheel is entirely out of the cup, and the flute-feed feeds the grain just as it does separately or when used by itself; but the two together work in such manner as to feed any desired amount of grain without any bunching, the rim-feed coöperating with the flute-feed to produce that desired continuity of feed which the ordinary flute-feed lacks. I thus have the advantages of a rim-feed combined with those of the flute-feed, the two coöperating with each other to produce the desired result.
- 20 By having the outside rim of the rosette uncovered the grain resting on the top thereof is carried down into the bottom of the cup, and the provision of the tapering flange c gives the grain a slight impetus toward the outlet, which greatly assists and facilitates the feeding of the grain.
- Having thus described my invention, what I desire to claim as new and to cover by Letters Patent is—
- 30 1. In a force-feed seeding-machine, in combination with a grain-cup and cut-off, a combined rim and flute feed, the rim-feed being arranged to act, when the flute is pushed completely out of the grain-cup, substantially as and for the purpose described.
2. In combination with the grain-cup, cut-offs and fluted wheel, a rose-washer provided with a shallow flange sharply inclined to the vertical at its inner edge and having short ribs thereon, the gate of the cut-off terminating short of the inner end of the fluted wheel, substantially as and for the purpose described.
3. In a force-feed seeding-machine, the combination with the seed-cup, of a force-feed seed-wheel, a rotating rose-washer provided with an inwardly-projecting flange, with the inner edge thereof sharply inclined to the vertical and having ribs and a cut-off gate terminating short of the end of the feeding-wheel, substantially as and for the purpose described.
4. In a force-feed seeding-machine, the combination with the seed-cup, of a force-feed seed-wheel, a cut-off gate arranged to leave a space between it and the end of the feed-wheel, and a revolving washer provided with a flange sharply inclined to the vertical at its

inner edge and having ribs thereon, substantially as and for the purpose described.

5. In a force-feed seeding-machine, the combination with the seed-cup, of a force-feed seed-wheel, a cut-off gate arranged to leave a space between it and the end of the feed-wheel, and a revolving washer provided with a flange inclined to the vertical at its inner edge and having ribs thereon, substantially as and for the purpose described.

6. In a force-feed seeding-machine, the combination with the seed-cup, of a force-feed seed-wheel, a cut-off gate arranged to leave a space between it and the inner end of the feed-wheel, said gate being flush with the lip of the cup, and a revolving washer provided with a flange inclined at its inner edge and having ribs thereon, substantially as and for the purpose described.

7. In a force-feed seeding-machine, the combination with the grain-cup, cut-offs, and force-feed wheel, of a revolving washer of a diameter of substantially the depth of the cup, the upper edge of said washer being entirely uncovered and being in the plane of the upper edge of the grain-cup, substantially as and for the purpose described.

8. In combination with the grain-cup, cut-offs and force-feed wheel, a revolving washer suitably mounted in the grain-cup with its upper edge flush with the top thereof, said cup being provided with a tapering flange, which covers the outer edge of said washer toward the outlet of the cup, substantially as and for the purpose described.

9. In a force-feed seeding-machine, the combination with the seed-cup, of a force-feed seed-wheel, a cut-off gate arranged to leave a space between it and the inner end of the feed-wheel and being in the plane of the lip of the seed-cup, and a revolving washer provided with a flange inclined at its inner edge and having ribs thereon, said washer having its top uncovered, substantially as and for the purpose described.

10. In a force-feed seeding-machine, in combination with the seed-cup and lip thereof, and the force-feed seed-wheel and rose-washer, a cut-off gate terminating short of the inner end of the force-feed seed-wheel, its upper face being in the plane of the seed-cup lip, substantially as and for the purpose described.
